BLOWER

Carl E. Wilken, New Lebanon, Ohio, assignor to
The Lau Blower Company, Dayton, Ohio, a corporation of Ohio

Application December 17, 1945, Serial No. 635,454

15 Claims. (Cl. 230—134)

1

This invention relates to multiblade centrifugal fans of the type commonly known as blowers and to rotors or blower wheels therefor.

It is the principal object of the invention to provide an improved blower wheel which is simple and economical in construction, which can be made at less expense than wheels heretofore available, which has individual blades shaped to develop the most desirable performance and air delivery, and which is of high strength and rigidity and capable of operating with freedom from objectionable vibration and noise at high speeds.

It is a further object to provide a blower wheel having a plurality of separately formed blades which are held in operative position without the use of welded or riveted joints and which has good balance and concentricity as initially formed and in operation.

It is a further object to provide a blower wheel made up of separate blades which are assembled and securely held in proper operative position without the use of any heating operation making possible the use of blades which have been galvanized or otherwise surface treated, and further enabling the use of non-metallic blade materials where desired.

It is also an object to provide a spun end ring construction for such blower wheels which securely locks the blades in operative relation in the wheel requiring no welding, riveting, or the like and providing great strength, stiffness, and concentricity.

It is a further object to provide a blower wheel which has a maximum effective length of the blades with only a relatively small space required at the ends for blade retention.

It is also an object to provide a blower wheel of the double inlet type having a center disk against which the blades are drawn and compressed under the action of the end rings providing a pre-stressed condition in the blades.

It is also an object to provide a method of forming such a blower wheel including the spinning of an end ring into locking position to retain the blades in assembled relation, the spinning operation being accomplished quickly and easily and tending to promote concentricity and proper balance of the wheel.

It is also an object to provide a novel method of making the wheel in motion providing for developing inherent concentricity and precision.

Other objects and advantages will be apparent from the following description, the accompanying drawings and the appended claims.

2

In the drawings:

Figs. 1, 2 and 3 are respectively a side elevation, a plan, and a partial perspective of an individual blade for a blower wheel constructed in accordance with the present invention;

Figs. 4, 5 and 6 show three sequential steps in the assembly of the blades and the end rings in the spinning operation;

Fig. 7 is a section through the blade on the line 7—7 of Fig. 6;

Fig. 8 is a broken section through the end flange and the end ring of the blade on the line 8—8 of Fig. 6;

Fig. 9 is a transverse section on the line 9—9 of Fig. 6;

Fig. 10 is a side elevational view of the fixture used for holding the blades in proper position during the spinning operation;

Fig. 11 is a section view on the line 11—11 of Fig. 10;

Fig. 12 is a view of the assembled wheel of the double inlet type with portions broken away indicating the pre-stressed condition of the blades;

Fig. 13 is a partial end elevational view on the larger scale of the finished wheel with a portion of the end flange broken away;

Fig. 14 is a perspective view of the finished wheel of the double inlet type;

Figs. 15 and 16 are sectional views on an enlarged scale of a different form of end ring and lock for the end flange;

Fig. 17 is a sectional view showing the application of the invention to a wheel of the single inlet type; and

Fig. 18 is a vertical sectional view through the wheel in its assembled operative position in a housing constructed to develop high overall output and efficiency.

Blower wheels may be constructed from an integral sheet of material by stamping the blades from the sheet in the form of louvers, or the wheel may be assembled from a group of individual and separately formed blades which are then secured in proper operative relation. If the wheel is made from a continuous or integral sheet, the limitations inherent in this construction make it impracticable to use the most advantageous form of blade, i. e., as to depth, angle, and spacing from adjacent blades, to develop the maximum output from the blower. In accordance with the present invention, a construction incorporating separate blades is utilized making it possible to form the blades in the

shape found most desirable for developing maxi-

mum performance, and without the inherent limitations arising from the use of an integral sheet. Thus for example by using separate blades they may have a relatively large depth of face and may be spaced close together making it possible to obtain substantially improved performance.

In addition the present invention provides a construction which avoids the necessity for separately mounting and fastening the individual blades in place, and avoids the use of riveting or welding operations which require a substantial amount of skilled workmanship in order to produce an acceptable finished blower wheel. In the present construction the blades are assembled rapidly and without individual manual handling for securing the blades in place, the securing of the blades in assembled position being effected without the use of riveting, welding, or similar operation requiring the use of heat. As a result, it is entirely practicable with the present invention to utilize blades which have been galvanized or otherwise coated or treated for rust prevention, the securing of the blades in proper assembled relation in the absence of a step involving heat resulting in the maintenance of the protective or rust proof coating substantially unimpaired while at the same time avoiding the deforming stresses which accompany such heating steps. It is even possible to make use of blades of non-metallic material, such for example as plastic or the like, which may be easily assembled in the same manner.

The blower wheel as so produced not only secures the blades in assembled position but accomplishes the assembly in a manner which tends to assure accurate concentricity of the entire wheel about the axis on which the wheel will rotate in use. The assembly is effected by spinning an end ring in position over outwardly extending end flanges formed on the blades, and with the spinning of the rings in position, a bending stress is developed in the blades which tends to draw them uniformly into accurate and concentric position, the wheel being rotated in the operation about the axis on which it will rotate in use. This has been found to contribute quite substantially to obtaining the proper balance of the wheel, making it a relatively simple matter to effect the final balancing of the finished wheel. If balancing weights are required, they are relatively small and thus balance obtained at one speed is much more nearly correct at higher speeds than is the case where through manufacturing variations it is necessary to add weights of considerable size, establishing a localized mass which may create unbalanced forces and tend to cause vibration when rotated under operating speeds.

The end ring may be suitably made of material of high tensile strength and thus contributes substantially to the strength of the assembly, providing a materially stronger wheel which can be operated reliably, without danger of vibration, noise, or mechanical failure, at speeds materially above the normal operating speed. Also the end ring provides a smooth and continuous outer periphery affording protection to the blades themselves but may be made quite narrow in its inward extent, leaving the major portion of the inner ends of the blades uncovered, thus further contributing to improved performance of the wheel in use.

The invention likewise provides for the support of the blades from the drive member in such

manner that the drive takes place directly to each blade, thus establishing balanced mechanical forces and loadings, and avoiding the transmission of concentrated or unbalanced stresses through the structure where the support is provided at only a relatively few points.

Referring now to the drawings which illustrate a preferred embodiment of the invention, a typical blade construction is shown in Figs. 1, 2 and 3 where the blade is shown as having a curved working face 10 which is arcuately shaped in a uniform manner over the major portion of the length of the blade. At either end the wall of the blade is turned over at approximately right angles as shown at 12 forming a laterally extending wall on the convex side of the blade. Beyond the wall 12, the material of the blade is flanged as shown at 13, this flange being bent upwardly at right angles to the longitudinally extending blade surface, the flange thus projecting radially outwardly of and overhanging the working face of the blade. As shown the flange is tangent to one side of the working face 10 at approximately the point 14, and the end wall 12 is thus of varying width of face as clearly appears in Fig. 3. Also the outer periphery of the flange 13 may be either flat or arcuate as shown at 15 about a radius corresponding to the radius of the blower wheel.

The blades are preferably notched at their inner central portions as indicated at 16, and the blades are all die stamped and formed from a single continuous sheet of material. With such construction a corresponding notch is formed on the opposite side of the blade, but this latter notch is of no particular value so far as the operation of the device is concerned.

The blades are assembled in parallel relation about the circumference of a center disk member shown at 20. The disk has notches 21 spaced around its outer periphery in corresponding number and angular relationship to the individual blades. The disk may conveniently be formed by stamping and pressing a pair of sheet metal plates with a centrally offset portion shown at 22 forming lateral extensions on which hub members 23 are secured. This provides a support for receiving the shaft of the wheel, suitable fastening means such as set screws 24 providing for securing the wheel to the shaft in proper working relation.

In the assembly of the blades they are loosely fitted into place each with its inwardly extending notch 16 engaged in the corresponding notch 21 of the center disk. End rings indicated generally at 25 are suitably positioned at either end of the blades, providing for receiving the outwardly extending blade flanges 13 therein as the blades are progressively stacked in place. This operation is performed quite readily with the blades being introduced into proper position within the end rings and in engagement with the notched center disk, as the center disk is slowly rotated on the shaft. As will be evident from Fig. 4, the end ring 25 is provided with an offset shoulder portion 26 and an inwardly projecting flange portion 27 which is adapted to interfit with the projection formed by the overhanging end flange 13. The projections on the ends of the blades thus are received within the end rings and supported loosely on the shoulders 26 with the flanges 13 extending radially outwardly. The number of blades and the peripheral extent of their end flanges is preferably such

that they are not in contact with each other but some clearance therebetween is provided.

The assembly and proper spacing of the blades is facilitated by the use of the fixture arrangement shown in Figs. 10 and 11. As there shown, the blades 10 are placed in a fixture comprising a notched retaining disk 30 which is bolted as shown at 31 in proper spaced relation with respect to an adjustable end plate 32 keyed as shown at 33 to a shaft 34. An adjustable nut 35 provides for the setting of the end plate in predetermined axial relationship with respect to a fixed plate 36 at the opposite end of the shaft and also rotatable therewith. Each end plate has a shoulder 37 formed thereon on which the 10 shouldered part 26 of the end ring 25 is adapted to be received, the flange 28 of the end ring being open as shown. Disk 30 is provided with a series of tapered notches 40 around its periphery which lead through a restricted neck portion 41 into a series of inner drilled apertures 42, a pair of bowed spring members 43 being arranged on each side of the notch in position to yieldably and frictionally engage the surface of each blade as it is inserted radially into the notch. It will be clear from Fig. 11 that the outer periphery of the disk 30 is substantially less than that of the end plates and it can thus be withdrawn axially of the blades without disturbing their assembled relation.

In the assembly of a wheel in accordance with the present invention, a center disk 20 is first located on the shaft 34 at a central position thereon, and the continuous end rings 25 are positioned in the shoulders 37 of the oppositely facing plates 32 and 36. The shaft 34 is then revolved slowly while the individual blades 10 are assembled using the notches 40 of the disk 30 as a guide for receiving the blades and temporarily holding them in proper assembled relation with their center notches engaged in the corresponding notches of the center disk 20. The blade flanges 13 are received in the end rings at opposite ends in the relationship illustrated in Fig. 4. If desired a similar disk 30 may be positioned adjacent the fixed plate 36, although it has been found that a single such plate will function satisfactorily. The blades are easily slipped into position between the springs 43 with their bottom edge seating in the respective apertures 42 and the stacking continues in this manner until a complete set of blades is assembled.

When the blades are properly assembled, the adjustable end plate 32 is moved axially of the shaft by the tightening of nut 35 to compress the two end plates toward each other and thus assure the proper axial alignment of all individual blades and at the same time bringing the respective end rings into tight relation therewith and with the shoulders 26 engaging under the overhanging blade end flanges.

The fixture is then rotated, which may be conveniently accomplished by placing the shaft 34 in a lathe and suitably driving the fixed plate 36 in the usual way. A spinning tool indicated diagrammatically at 45 is then brought into working relation with the two end rings 25 to effect the spinning of the rings into final gripping and locking relation with the end flanges of the plates. This operation begins by the pressing downward of the inwardly projecting part 28 of the end ring, the spinning tool being brought to bear against this portion of the ring to cause it to turn over and move downwardly toward the outer surface of the blade as shown in Fig. 5. As this

operation is completed, the spinning tool moves radially inwardly and the material of the portion 28 of the end ring is drawn forcibly into contact with the series of blade flanges 13, causing a firm and secure interlocking action which serves the desirable purpose of retaining the blades in proper position in use. The end ring is drawn downwardly against the outer peripheries of the end flanges, the extent of the actual contact therewith depending upon whether the end flanges are flat or conform to the circular shape. This operation also tightens the outer portion of ring 25, drawing the shoulder 26 forcibly up against the overhanging projection at the base of end flanges 13.

As shown in Fig. 6, the length of the portion 28 of the end ring is preferably such that it is longer than the height of flange 13 and thus in finished position a lip 50 is formed on the inner portion of the ring, bearing against the outer surface of the blades and extending axially of the blades toward the ring on the opposite end.

As shown in Figs. 7, 8 and 9, the width of the peripheral extent of flanges 13 is so limited that small clearances or gaps 55 are provided between adjacent blades. The actual dimensions of these gaps need not be large, but it is found that where even a limited space is thus available, a desirable interlocking action is secured. The gaps should be present at least at the outer peripheries of the flanges 13 and may continue radially inwardly so that as shown in Fig. 8 adjacent blades are actually separated from each other at all points.

This locking action is provided in the following manner. It is found that the spinning operation may be made to develop substantial forces in the material of the end ring tending to draw or work the metal into the gaps provided between the end flanges of the blades. This results in forming small projections which extend into the gaps 55 and interlock each blade to hold it securely in position in the end rings. The material of the end ring 25 is drawn tightly around the outer peripheral surface 15 of the end flanges and in part into the gaps between those flanges, the pressure being such as to cause the material to be drawn or to flow somewhat into the gaps as indicated at 56, thus forming a series of inward projections between each pair of adjacent blades. These projections on the outer periphery of the end ring in conjunction with the gripping action afforded by the U-shaped section of the end ring engaging opposite sides of the flanges serve to firmly retain the blades in assembled relation against relative movement or vibration and provide a strong and a highly advantageous device. Further, the spinning operation may be made to so work the metal forming the vertical face of wall 28, that it tends to flow into the gaps 55 between the sides of the flanges 13 as shown by projections 58. While the outer surface 59 of this portion of the end ring may retain a substantially smooth appearance because of the action of the spinning tool, the presence of such interlocking inward projections 58 extending into the gaps between adjacent flanges provides a further locking action of all of the blades in proper operative relation.

Still further, the spinning of the lip 50 may develop projecting portions 60 which extend into the gaps between adjacent blades, thus further contributing to the desired locking action. It will be understood that it is not essential that all of these groups of locking projections be formed,

but one or more of the interlocking actions may be utilized as desired.

Since this spinning operation is carried out while the assembly is being rotated about the actual axis of rotation of the finished wheel, the spinning action itself promotes desired concentricity, and tends to develop a greater stress upon any blade or portion thereof which tends to project radially outwardly from the others with the result that the finished wheel following the spinning operation is found to require very little additional balance. This not only simplifies the manufacturing process, but provides for better operating conditions without the use of large weights.

Preferably the spinning operation is so carried out that a definite confining stress is developed in the end rings to bow the blades inwardly against the center disk 20. This is illustrated in Fig. 12 in a somewhat exaggerated way, the blades 10 shown as being drawn together at their opposite ends so that the ends are pulled radially inwardly from the dotted line positions illustrating the normal position which such blades would occupy. This bending action is easily accomplished by the proper application of pressure to the end rings in the spinning operation, and is further desirable since it provides for secure locking interengagement between the central notches of the blades and the center disk assembly 20. It will be noted by examination of Fig. 12 that the bowing of the blades takes place in two planes, i. e., in the vertical plane as shown by the blades illustrated at the top and bottom of the wheel and also in the horizontal plane by the blades as shown in elevation at the center of the wheel. Each blade thus has a double or complex bowed relation subjecting the blade to a torsional deformation, the bow preferably being against the direction in which the wheel will rotate in use.

Following the spinning operation the fixture is removed from the lathe or other rotating support and nut 35 is removed, providing for the withdrawal of end plate 32 which likewise effects withdrawal of the disk 30 from its contact with the inner edges of the blades, without however disturbing the blades in their now completely assembled relation. The finished wheel may then be removed from the shaft and the fixture reused for the formation of another wheel.

A wheel constructed in accordance with the present invention has been found to have a high degree of mechanical strength. This is made possible by the flanged construction at the end of the blade and the similarly flanged and shouldered construction of the end ring which engages the blade flanges. As will be evident, the shoulder 26 and the lip 50 of the end ring both extend at right angles to the remaining portions of the end ring and in such manner as to add substantially to its strength and stiffness. The finished ring is spun into the construction shown and provides a firm and sturdy construction, securely fixing the blades in proper relation, and preventing vibration, noise, or failure at speeds even several times the normal speed. As will be evident, the end ring is relatively narrow and preferably is so confined that it leaves the major portions of the ends of the blades free and unobstructed. Thus while the end ring provides a continuous flange around the outer circumference of the wheel, forming a support for the wheel which tends to prevent damage to the edges of the blades themselves, the

radially inner portions of the blades are left substantially uncovered at the ends, contributing to substantially improved performance of the wheel. As is clearly shown in Fig. 7, for example, the innermost extent of the portion 27 of the end ring is such that the major part of the working surface of the blade is left free at its end. This has been found advantageous from the standpoint of providing better performance and output characteristics, the structure at the same time assuring adequate strength and rigidity.

As shown in Fig. 13 the maximum diameter of the center disk portions 20 is less than the inner diameter of the annular end ring members, and for convenience and economy of manufacture it is desired to form the center disk structure from the stamping cut from the metal sheet in the forming of the end ring, thereby providing for substantially eliminating waste material in the operation.

It will be evident from the above disclosure that the entire assembly of the wheel is accomplished without the use of riveting, welding or other operations involving the use of heat. The wheel is therefore not subjected to strains resulting from wide temperature changes, does not have the lack of uniformity encountered in the making of individual welded or riveted joints, and assures both greater strength, and concentricity. It is evident therefore that the blades may be made of galvanized material or otherwise treated to prevent rust or chemical action, the spinning of the end rings to retain the blades in position being an operation which does not adversely affect such treated surfaces. As above stated, it is also possible to form the blades from molded plastic or other non-metallic materials having the necessary strength.

Different constructions of end ring securing means may be used and an alternate construction is shown by way of example in Figs. 15 and 16 which are sectional views on an enlarged scale showing two steps in the formation of such modified construction. As shown the blade 64 has an end flange 65 which is generally similar to the end flange 13 described above, the blade end in this case being shown curved as indicated at 66, since the flat ended blade form previously described is not required in all cases. The ring 67 is provided which is received over and engages the radially outer peripheries of the flanges 65. The radially inner end of the ring is shown at 68 being offset to be received under the overhanging projection of the end flange of the blade and terminating in a bent portion 69 which is spaced from the curved end 66 of the blade as shown. After the end ring is positioned over the end flanges of the blades as shown in Fig. 15, the portion 67 is turned or spun downwardly to overlap the series of end flanges and the overlapped parts then folded down flat upon themselves into the shape shown in Fig. 16. This is conveniently done by a spinning operation similar to that described above, and such operation may also develop the interfitting projecting portions in the gaps between the blades, in the manner already described. When the parts are folded flat upon themselves, a completely effective lock is thus provided assuring the tight retention of the blades in the end ring firmly and in whatever spaced relation is desired.

While the above description refers to double inlet wheels, it will be evident that it is also applicable to single inlet wheels. An example of this latter construction is shown in Fig. 17 in

which the end ring 70 at the open end of the wheel is substantially similar in construction and its manner of formation to the construction described above. At the closed end, a plate 72 is centrally apertured to receive the bearing 73, the plate having suitable offset portions as shown at 74 and 75 to provide added stiffness. The outer periphery of the plate 72 is formed as shown at 76 in the same manner as the end ring construction, and is spun into securing relation with the end flange 77 on blades 78 in a manner similar to that already described.

Referring to Fig. 18, a blower is shown incorporating a blower wheel of the present construction in a housing comprising a casing 80 which is provided with a flange 81 on its base and having a spiral air delivery chamber 82, the wheel being centered axially between the opposite ends of the casing. For most satisfactory blower operation it has been determined that the diameter D of the wheel measured to the outer periphery of the blades should approximately equal the axial length of the blades. Further as will be evident from the arrangement shown in the drawing the inlet for either end should be formed by curved inlet members 84, 85, the radius R of which has a relation to the diameter of the wheel for best operating results. Thus it will be seen that the inlet opening is approximately the same as the inner diameter of the blades, and is relatively closed spaced thereto. For best operating results the casing itself should have a definite spacing axially beyond the ends of the blower, i. e., the dimension marked A on the drawing having a definite relationship to the diameter of the wheel. Very satisfactory results have been secured where the dimension A is approximately 12 to 14% of the diameter of the wheel while the radius R of the inlet ring is approximately 9 to 10% of the diameter of the wheel. It will also be noted that the housing is shown as comprising a plurality of arms 87, preferably three in number, for supporting the bearings 88 in which the blower shaft 89 is journaled, the arrangement of such arms being desirable as not adversely affecting the air supply to and the output of the blower. Suitable resilient members are provided in such supporting arms for resiliently mounting the blower shaft.

The above invention thus provides a simple and highly satisfactory blower wheel construction embodying new and desirable features of construction which provide for developing superior performance and output while at the same time furnishing a maximum of strength and stiffness in the finished wheel. The formation of the wheel is very simple, and takes place rapidly and without individual handling of the separate blades, not only saving in the time required for individual blade attachments but further materially saving in the finishing time required to accomplish proper balancing of the blade.

Reference is made to copending application, Serial No. 784,335, filed November 6, 1947, as a division of the present application.

While the forms of apparatus and process herein described constitute preferred embodiments of the invention, it is to be understood that the invention is not limited to these precise forms of apparatus and process, and that changes may be made therein without departing from the scope of the invention which is defined in the appended claims.

What is claimed is:

1. A centrifugal blower wheel comprising a plurality of separate blades, each said blade having a flange at the end thereof extending radially of said wheel, said blades being arranged around the periphery of said wheel with gaps between adjacent flanges, and a continuous retaining ring secured in position over said flanges and indented in interlocking relation into the gaps between adjacent said blades for holding the blades in operative position with said flanges spaced from each other to form said wheel.

2. A centrifugal blower wheel comprising a plurality of separate blades, each said blade having a flange thereon extending radially of said wheel, said blades being arranged around the periphery of said wheel with gaps between adjacent flanges, and a retaining ring having portions thereof indented in interlocking relation to the gaps between said flanges for holding said blades in assembled relation to form said wheel.

3. A centrifugal blower wheel comprising a plurality of separate blades each having a flange thereon extending radially outwardly of the wheel in a direction substantially normal to the axis of the wheel with radially extending gaps between adjacent flanges, and a single continuous retaining ring overlying said flanges and having radially extending portions interfitting into said gaps to retain said blades in assembled position.

4. A centrifugal blower wheel comprising a plurality of separate blades each having a flange at the end thereof extending radially outwardly in a plane substantially normal to the axis of the wheel with gaps between adjacent flanges, and a continuous ring substantially U-shaped in cross-section overlying and enclosing said flanges on opposite sides thereof to retain said blades in operative position forming said wheel, the axially outer surface of said ring being substantially smooth and the axially inner portion thereof being indented into the gaps between said flanges.

5. A centrifugal blower wheel comprising a plurality of separate blades circumferentially arranged to form a wheel, each said blade having a flange formed thereon at its opposite ends extending radially outwardly thereof, said blades being spaced from each other around the periphery of said wheel by small gaps, and a retaining ring received over and enclosing said flanges, the material of said ring extending into said gaps between adjacent said blades to provide an interlocking construction for retaining said blades in assembled working relation with each other.

6. A centrifugal blower wheel comprising a plurality of separate blades circumferentially arranged to form a wheel, each said blade having a flange formed thereon at its end extending radially outwardly thereof, said blades being spaced from each other around the periphery of said wheel by small gaps, and a retaining ring spun in position over said flanges and having portions thereof interlocking into said gaps between adjacent said blades to provide for securely retaining said blades in assembled position.

7. A centrifugal blower wheel comprising a plurality of separate blades circumferentially arranged to form a wheel, each said blade having a flange formed thereon at its end extending radially outwardly thereof, said blades being spaced from each other around the periphery of said wheel by small gaps, and a retaining ring spun in position over said flanges and forming a lip extending axially inwardly of said

wheel from the portions enclosing said flanges.

8. A centrifugal blower wheel comprising a plurality of separate blades circumferentially arranged to form a wheel, each said blade having a flange formed thereon at its opposite ends extending radially outwardly thereof, said blades being spaced from each other around the periphery of said wheel by small gaps, and a retaining ring spun in position over said flanges and having portions thereof extending from the outer periphery of the ring into the gaps between adjacent flanges to lock said blades in place.

9. A centrifugal blower wheel comprising a plurality of separate blades circumferentially arranged to form a wheel, each said blade having a flange formed thereon at its opposite ends extending radially outwardly thereof, said blades being spaced from each other around the periphery of said wheel by small gaps, and a retaining ring received over said flanges with the axially inner wall thereof spun in position over said flanges and in interlocking engagement into said gaps to firmly secure said blades in assembled relation.

10. A centrifugal blower wheel comprising a plurality of separate blades circumferentially arranged to form a wheel, each said blade having a flange formed thereon at its opposite ends extending radially outwardly thereof, said blades being spaced from each other around the periphery of said wheel by small gaps, and a retaining ring received over said flanges with the axially inner wall thereof spun in position over said flanges and into contact with the body of said blades, said inner wall having portions thereof extending into said gaps between adjacent flanges to lock said blades in place.

11. The method of forming a blower wheel from a group of separately formed blades having outwardly extending end flanges thereon which comprises assembling said blades into the form of a wheel, temporarily supporting said blades with portions of their adjacent end flanges spaced from each other, spinning an end ring into position over said end flanges to cause projections thereon to extend into the spaces between said adjacent end flanges to lock the blades in proper operative relation, and thereafter withdrawing the temporary support to leave the finished wheel with the blades in completely assembled relation.

12. A centrifugal blower wheel comprising a plurality of separately formed blades arranged around the periphery of the wheel each having a flange at the end thereof located radially outwardly of the formed surface of the blade and extending radially outwardly with respect to said formed surface, each said blade having a turned-over wall extending laterally from the convex side thereof, and a continuous retaining ring secured in gripping position over the flanges of said blades for holding said blades in position to form said wheel, said ring having a flat portion extending generally radially of the wheel and overlying said turned-over wall portions of said blades over a relatively narrow extent thereof leaving

the major portion of the inner ends of said blades uncovered providing for improved performance of the wheel in use.

13. A centrifugal blower wheel comprising a plurality of separately formed blades arranged around the periphery of the wheel, a supporting disk engaging the inner portions of said blades intermediate the ends thereof, the inner diameter of the outer ends of said blades in the finished wheel being less than the inner diameter of said blades at said disk, and end rings engaging the ends of said blades outwardly of said disk retaining the ends of said blades inwardly at said lesser diameter causing the bowing of said blades with a maintained stress condition therein.

14. A centrifugal blower wheel comprising a plurality of separately formed blades arranged around the periphery of the wheel, each said blade having end flanges extending radially outwardly of said wheel, a supporting disk having a peripheral portion interengaging with the inner portions of said blades intermediate the ends thereof, the inner diameter of the outer ends of said blades in the finished wheel being less than the inner diameter of said blades at said disk, and end rings engaging the end flanges of said blades retaining the ends of said blades radially inwardly at said lesser diameter causing the bowing of said blades with a maintained stress condition therein.

15. A centrifugal blower wheel comprising a plurality of separate blades circumferentially arranged to form a wheel, each said blade having a flange at its opposite end overhanging the working face of the blade and extending radially outwardly of the wheel, and an annular ring closely engaging said flanges and having a lip on its axially inner portion adapted to be received in reinforcing engagement with the outer edges of the working surfaces of said blades.

Certificate of Correction

January 9, 1951

Patent No. 2,537,805

CARL E. WILKEN

It is hereby certified that error appears in the printed specification of the above numbered patent requiring correction as follows:

Column 9, line 31, for "closed" read *closely*; column 10, line 18, for "to" read *into*; column 11, line 53, after the word "formed" insert *curved*; and that the said Letters Patent should be read as corrected above, so that the same may conform to the record of the case in the Patent Office.

Signed and sealed this 17th day of April, A. D. 1951.

[SEAL]

THOMAS F. MURPHY,
Assistant Commissioner of Patents.
